UNITED STATES PATENT OFFICE

162,646

COMBINED SPEAKER AND SUPPORT
THEREFOR

Dana G. Griffin, Fort Worth, Tex.

Application March 23, 1950, Serial No. 8,714

Term of patent 3½ years

(Cl. D26—14)

To all whom it may concern:

Be it known that I, Dana G. Griffin, a citizen of the United States and residing at Fort Worth, in the county of Tarrant and State of Texas, have invented a new, original, and ornamental Design for a Combined Speaker and Support Therefor, of which the following is a specification, reference being had to the accompanying drawing, forming part thereof.

I claim:

The ornamental design for a combined speaker and support therefor, substantially as shown and described.

DANA G. GRIFFIN.
